UNITED STATES PATENT OFFICE.

JUDSON L. BASSETT, FRANKLIN W. BASSETT, AND ALPHONSO E. HUTCHINS,
OF COLDWATER, MICHIGAN.

PICTURE-EXHIBITOR.

SPECIFICATION forming part of Letters Patent No. 280,556, dated July 3, 1883.

Application filed November 29, 1882. (No model.)

To all whom it may concern:

Be it known that we, JUDSON L. BASSETT, FRANKLIN W. BASSETT, and ALPHONSO E. HUTCHINS, citizens of the United States, residing at Coldwater, Branch county, Michigan, have invented certain new and useful Improvements in Picture-Exhibitors; and we do hereby declare that the following is a full, clear, and exact description of the same, reference being had to the accompanying drawing, in which the figure is a perspective view of our invention.

The invention has relation to picture-exhibitors for displaying and protecting photographic and other views; and it consists in the construction and novel arrangement of parts, as will be hereinafter fully described, and particularly pointed out in the claim appended.

Referring by letter to the accompanying drawing, A designates a stand for the rotary cylinder, the said cylinder C having its bearings in the vertical sides of an ornamental frame, B, the ornamentation forming no part of the invention, but being resorted to as a matter of taste. The cylinder C is octagonal or polygonal in form, and is provided with slideways F for the glass slides D, to which the photographs or views to be exhibited are secured.

The photographs or views are to be secured 30 to the under faces of the glass slides D, in order that they may be protected from dust when in place in the slideways F. The journals of the cylinder are provided with hand-pieces E, by which the cylinder C may be rotated to expose any one of its faces. 35

This device affords a very convenient means of exhibiting photographic and other views, and is, besides, an ornament to the parlor.

The glass slides may be removed and replaced at pleasure by new views or photographs. 40

Having thus fully described our invention, what we claim as new, and desire to secure by Letters Patent, is— 45

The combination, with the stand A, having the frame B at its top, of the octagonal or polygonal cylinder C, provided with the removable glass slides D and the hand-pieces E, substantially as specified.

JUDSON L. BASSETT.
FRANKLIN W. BASSETT.
ALPHONSO E. HUTCHINS.
